UNITED STATES PATENT OFFICE.

DILMAN BRUBACHER SHANTZ, OF BERLIN, CANADA.

MACHINE FOR TURNING BUTTONS.

SPECIFICATION forming part of Letters Patent No. 497,349, dated May 16, 1893.

Application filed July 25, 1892. Serial No. 441,132. (No model.)

To all whom it may concern:

Be it known that I, DILMAN BRUBACHER SHANTZ, manufacturer, of the town of Berlin, in the county of Waterloo, in the Province of 5 Ontario, Canada, have invented certain new and useful Improvements in Machines for Turning Buttons, of which the following is a specification.

My invention relates to improvements in 10 machines for turning buttons and similar articles and the object of the invention is, first, to provide mechanism whereby the tools may be made to operate upon the blank so as to quickly turn both the back and front of the 15 button into shape and then much more gradually operate upon the partially finished button so as to turn it out perfectly finished; secondly, to provide a means whereby each jaw on the intermittently revolving disk which 20 holds the blanks may be forced open so as to drop the remnant of the blank after the turning of the button and held open so as to give time for the placing and gripping of the blank between the jaws during the period that the 25 cutters are operating upon the preceding blank; thirdly, to provide mechanism whereby the jaws will not only hold the blank securely during the period that it is moving into position but further will retain the jaws 30 upon blanks so as to withstand the action of the cutter and prevent it from throwing the blank out of position in the jaws during the period that the button is being turned; fourthly, to provide an adjustable shield where- 35 by the button when completed may be prevented from being thrown against the opposite cutter and having the front surface of the button defaced; fifthly, to provide a simple means for rotating the disk containing the jaws 40 as stated at regular intervals so as to bring the jaws opposite the cutters, and sixthly, to provide a means whereby the disk may be held perfectly rigid during the period that the 45 cutters are operating to turn the button, and it consists essentially, first, of connecting the ends of the cutter spindles to levers which are pivoted at the top of the frame of the machine and are reciprocally adjustable during the revolution of the spindles by cams of pec- 50 cular construction which operate within a cage connected to the lower end of the levers; secondly, of providing a pin on the in-

ner end of the spring jaws, which pin extends through the disk upon which the jaws are pivoted and comes against and is designed 55 to travel upwardly against the inner face of a spring arm so as to hold the jaws open until released by the operator; thirdly, of forming the adjustable pivoted half of the jaw in two parts and providing a spring to 60 normally hold the two parts of the one half against the other half and further in providing a split plunger each half of which is connected to a pivoted lever which is held by springs at its bottom end so that each half of 65 the split plunger will maintain an equal pressure against its corresponding part of the adjustable half of the jaw and thereby insure a blank of unequal thickness being held securely between the jaws and also in providing 70 a plunger which is supported in bearings and is operated by a cam secured on one end of the main arbors so as to come against the lower arms of the levers and tilt them on their pivot so as to remove the split plungers from 75 their contact with the two parts of the adjustable half of the jaw when the button is finished and thereby allow of the disk rotating; fourthly, of a shield pivoted on the end of an arm which is connected by a rod to the top of 80 the cage within which one set of the main cams work; fifthly, of providing a ratchet pinion on the end of the main disk spindle which ratchet has a corresponding number of teeth to the open jaws within which the blank is 85 held and is operated by a pawl from a grooved cam on one of the main arbors; and, sixthly, of cutting notches in the main disk corresponding in number to the number of jaws and providing a dog which is brought at cer- 90 tain intervals by a cam into the notch and held there by a spring behind the dog, the whole being arranged and constructed in detail as hereinafter more particularly explained.

Figure 1, is a perspective view of my machine portion of the disk being broken away. Fig. 2, is a perspective view from the opposite side of the machine. Fig. 3, is a skeleton view showing the means of driving the disk 100 wheel, operating the split plunger, and the dog for holding the disk wheel stationary. Figs. 4 and 5, are details of blanks.

In the drawings like letters and numerals

- of reference indicate corresponding parts in each figure.
- A, is the main driving shaft which is supported in bearings in the frame of the machine and has worms, B, B', secured to it, which mesh with worm-gears, C, C', secured on the ends of the arbors D, D', which extend across the machine at right angles to the shaft A, and are supported in bearings in the frame, E.
- 10 F, is one cutter spindle and, G, the other. The cutter spindles, F, and, G, are provided with pulleys, F', and, G', and cutters, f, and, g, at the ends of the spindles, F, and, G, respectively. The spindles, F, and, G, derive a 15 rotary motion from belts which pass around the pulleys, F', and, G', respectively and are journaled in the frame of the machine as shown.
- H, and, H', are levers pivoted on the heads 20 of the screws, h, and h', which are adjustably secured in the standards, e, and, e' by jam-nuts, h'.
- I, and, I', are spring arms secured to the top of the lever, H, and extending partially across 25 the machine in the form shown. The free ends of the arms, I, and, I', are connected by the spiral springs, i, and, i', to the cross rod, J, which extends between the standards, e, and, e'.
- 30 j, and, j', are brackets secured at the center portion of the levers, H, and, H', and having the forked bent end as shown. The bent end of the brackets, j, and, j', extend into annular grooves, f', and, g', made in the end of the 35 cutter spindles, F, and, G, respectively.
- K, is the cam secured on the front end of the arbor, D. The arbor, D, revolves in the direction indicated by arrow and carries with it the cam, K.
- 40 L, is a cage having a screw spindle, l, extending from its outer end through the trunnion, M, pivoted in the lower end of the lever, H.
- N, and, O, are jam nuts situated one at each 45 side of the trunnion, M, and designed to adjust the screw spindle in relation to the lever, H. The trunnion, M, permits of the free horizontal movement of the cage, L. The inner end of the cage, L, has a supporting link, P, 50 which is connected at the top by the screw pin, p, and at the bottom by the pivot pin, q, which permit of the forward and backward movement of the cage, L.
- Q, is a supplemental cam arm pivoted at, r, 55 on the frame of the machine and extending up into the cage, L. The cam, Q, is provided with a portion, R, concentric to the center revolution of the arbor, D.
- k, is a series of rollers situated on the cam, 60 K. The curved line passing through the center of these rollers is concentric to the center revolution of the arbor, D. The rollers, k, are designed to come in contact with the concentric portion, R, of the cam arm, Q. As the 65 rollers pass the concentric portion, R, and the roller 2, passes over the concentric portion, 3,
- the cage is held perfectly steady. When the last roller, k, has passed the concentric portion, R, it rises upon and follows the curved portion, R'. The portion, 4, of the cam, K, 70 at the same time presses against the roller 2, and causes the cage to move in the opposite direction to that indicated by arrow and throws the cutter spindle, F, in the direction indicated by arrow. The curved portion, R', 75 is so arranged in relation to the cam, 4, that the distance between the last roller, k, on the cam, K, and the outside edge of the portion of the cam, 4, pressing upon the roller, 2, exactly fills up the space between the roller, 2, 80 and the curved portion, R', during the period that the roller, k, is ascending the curved portion, R'. When the last roller, k, has left the curved portion, R', the eccentric portion from, 4, to, 5, which is an eccentric of very slightly 85 increasing radii operates upon the roller, 2, so as to very gradually force the cage and consequently the cutter spindle forward thereby very slowly turning off the face of the button so as to leave a perfect finish on it. A concentric collar, 3, during this period is passing the minor concentric portion, R'', so as to hold the cage rigid in relation to the movement of the lever, H. When the point, 5, has been passed the spring, i, at the top of the arm, 95 I, operates so as to bring the roller, 2, on the cage in the direction indicated by arrow along the portion from, 5, to, 6, thereby causing the cutter to recede from the face of the button after it has finished it. During the 100 period that the roller, 2, is passing along the portion from, 5, to, 6, the first roller is approaching the point beneath the concentric portion, R, and rises and passes along the concentric portion, R, thus holding the cage 105 perfectly steady. As the roller, 2, passes along the portion from, 5, to, 6, it will of course be understood that the cutter spindle is caused to move in the opposite direction to that indicated by arrow and thereby withdraw 110 the cutter from the face of the button.
- K', is a cam secured on the outer end of the arbor, D'. The arbor, D', and cam, K', move in the direction indicated by arrow. The cam, K', is made upon larger radii than 115 the cam, K, so that the cutter, g, is brought up to the blank more quickly than the cutter f, and cuts more rapidly upon the back of the blank. Consequently the cutter, g, will start to operate upon the blank before the 120 cutter, f.
- Q', is a cam arm pivoted at, r', and extending up into the cage, L', as shown.
- k', are rollers made on the face of the cam, K'.
- l', is a screw spindle attached to or forming part of the cage, L', and extending through the trunnion, M', in the end of the lever, H'. N', and, O', are jam nuts situated on the screw spindle one on each side of the trunnion, M'. The cage, L', is supported at its 130 inner end by the link, P', which is pivoted

at the top on the screw pin, p' , and connected at the bottom to the cage, L' , by the pivot pin, q' . The portion, 7, of the cam, K' , starts to operate or press upon the roller, 8, at the same time that the portion, 4, of the cam, K , starts to operate or press upon the roller, 2, but as the cam, K' , is of larger radii than the cam, K , it moves the cutter, g , forward more quickly than the cutter, f . As the cam continues to revolve the eccentric portion, 7, of very rapidly increasing radii, causes the cutter, g , to move forward much more quickly than the cutter, f . During the first portion of the period that the portion, 7, of the cam, K' , is acting upon the roller so as to throw the cage, L' , in the direction indicated by arrow the last roller k' , passes up the curved upper portion, R''' , of the cam arm, Q' , thus holding the cage rigid in its relation to the movement of the lever, H' . When the last roller, k' , has passed the top point of the cam arm, Q' , the portion, R^4 , comes in contact with the concentric hub of the cam thereby also continuing to hold the cage rigid in relation to the lever, H' , until the leading roller, k' , reaches the position shown in the drawings when it mounts upon the then concentric portion, R^5 , which still continues to hold the cage rigid as to its relation to the lever, H' . This rigidity is maintained until the last roller passes the concentric portion, R^5 , and curved upper portions, R^4 , and, R^3 , and in fact throughout the whole movement of the cam. I should mention that when the point, 9, of the cam, K , passes the roller, 8, the cage is thrown in the opposite direction to that indicated by arrow by the spiral spring, i , a steady movement being maintained by the cam arm, Q' , as hereinbefore described.

It will be seen from what has been before described that the cams, Q , and, Q' , are designed to keep the cages, L , and, L' , rigid in relation to the movement of their levers, H , and, H' , which control the backward and forward movement of the cutters. They might, however, be dispensed with but I find in practice that it is preferable to provide these cam arms as the movement of the cutters both as they move forward to the blank and leave the finished button is very steady and consequently neither the face nor the back of the button will be defaced.

It will be seen on reference to the length of the operative cam, K' , in relation to the length of the operative part of the cam, K , that the cutter, g , will continue to move forward for a considerable longer period than the cutter, f , the cam, K , being so arranged that the cutter, f , will recede after having finished the face of the button while the cutter, g , is still moving forward to finish the back and sever the button from the blank. These forward and backward movements of the cutters, f , and, g , are regulated to take place when the disk is brought around so as to present the open jaws opposite the cutters.

The mechanism by which the disk is caused to revolve intermittently so as to bring the open jaws opposite the cutters and hold the disk steady I shall now describe. S , is the disk which is secured on the end of the counter shaft, s , journaled on the frame of the machine. In the disk shown in the drawings there are four notches, t . s' , is a ratchet-wheel secured on the opposite side of the counter shaft, s , and, s'' , is a pawl pivoted on the arm, T , which is loosely journaled on the end of the counter shaft s . T' , is a link connecting the arm, T , to the arm, U , secured on the rocking spindle, u . U' , is an arm secured at the opposite end of the rocking spindle, u , and having a pin, u' , which extends into a cam groove, u'' , in the collar, U'' , secured to the arbor, D . The rocking spindle, u , is journaled in suitable bearings in the interior of the frame of the machine. It will now be understood that every revolution of the worm wheel, C , arbor, D , and cam, K , with the cam groove, u'' , will cause the spindle, u , to rock and bring the pawl in the direction indicated by arrow so as to cause the ratchet pinion to move around in the direction indicated by arrow the space of one tooth, this distance being regulated by the cam groove, u'' . The off-set in the cam groove, u'' , is so arranged in relation to the cam, K , that it will operate to turn the disk, S , only during the period that the cage, L , lever, H , and consequently the cutter, f , is held stationary and away from the face of the blank. When the cam is operating so as to move the cutter backward and forward the pin, u' , at the end of the arm, U' , travels in the straight portion, u'' . It will consequently be seen that the disk, S , will always be held stationary during the period that the cutters are operating upon the blanks so as to turn and finish the button.

In order to provide a means which will hold the disk, S , perfectly rigid I provide a stop arm, V , which has a tooth, v , formed on the upper end which is designed to fit in the notch, t , in the disk, S . W , is a spiral spring which is located behind the stop arm, V , and is designed to hold the tooth, v , into the notch, t . In order to provide means whereby the tooth, v , may be removed from the stop arm when the button has been completed and fallen out I provide the following mechanism. The stop arm, V , is secured on the end of the rocking spindle, w , which is journaled suitably in the interior of the machine. X , is an arm secured on the other end of the rocking spindle, w , and having a pin, x , which fits the cam groove, x' , made in the collar, X' , secured on the arbor, D' . When the cutters have completed the button and it has fallen out the pin, x , reaches the off-set in the cam groove, x' , and rocks the stop arm, V , so as to withdraw it from the notch, t . The cam groove u'' , is so arranged that it will operate on the pin, u' , of the arm, U' , so as to bring the disk around to the next notch when the spring, W ,

will force the tooth, v , into the succeeding notch, t . This operation will take place after each button is completed.

I shall now describe the pivoted jaws and the means for holding them open and closed. 5 Y, are stationary portions of the jaws for holding the blank which jaws are secured in circular holes made in the disk, S. y, y' , are the two portions of the jaws which are pivoted at the center or hub portion of the disk as shown and are held normally against the stationary portion, Y, of the jaws by the spring, z. z' , are pins which are located behind the pivoted portions, y, y' . Z, is a stationary cam guide provided at the top with a handle, Z'. 10 When the disk, S, is caused to revolve as hereinbefore described the pin, z' , comes in contact with the lower portion of the stationary cam guide, Z, and travels along it. When the pin, z' , comes in contact with the cam guide it is forced inwardly so as to throw the jaws, y, y' , away from the stationary jaw, Y. The jaws now will travel around open until they reach the upper portion of the cam guide, Z, 15 at which period the disk, S, is caused to stop and is secured in position by the stop arm, V. It will now be seen that the jaws, Y, and, y, y' , will remain apart during the period that the cutters, f, and, g, are operating upon the preceding blank thus giving the operator 20 plenty of time to place the blank between the jaws, Y, and, y, y' . When the operator inserts the blank between the jaws, Y, and, y, y' , he pulls down the handle, Z', which as the cam guide is made of spring metal allows of it being withdrawn from behind the pin, z' , and the spring, z, connected to the jaws, y, y' , force the said jaws inwardly so as to securely grip the blank. When the cutters have turned 25 out their preceding button the stop arm is withdrawn from contact with the notch, t, in the disk, S, which is again caused to revolve bringing with it the next succeeding jaws, Y, and, y, y' , with the blank held between them. 30 When it has been brought around opposite the cutters the tooth of the stop arm is caused as hereinbefore described to drop in the notch, t, and thus hold the disk stationary. Each succeeding blank is inserted, held and comes 35 up into position in the same manner. I may here state that the one half of the jaws are made in two parts, y, y' , so that they may with greater facility hold a blank of unequal thickness and in order to provide an absolutely secure way of holding the jaws, y, y' , against the blank of unequal thickness I provide the split plunger, 10, which is made in two parts, 11, and, 12. The split plunger is supported in the socket, 13, and is cut away on 40 each side at, 14, as shown. 15, are two levers which are placed close together and are pivoted on the pin, 16, in the bracket, 13', forming part of the frame of the machine. The top end of each lever extends one at each side of the split plunger, 10, into the notch, 14. The lower

ends of the levers, 15, are connected by strong spiral springs, 17, to any suitable portion of the machine as indicated in Fig. 3. 18, is a plunger supported in suitable bearings in the interior portion of the frame of the machine. 70 19, is the head of the plunger which is of a diameter greater than from outside to outside of the edges of the two levers, 15. 20, is an annular groove made at the other end of the plunger, 18, and, 21, is a rocking arm pivoted on the arbor, D², provided with a friction roller, 22, at its upper end and an extension, 23, which fits into the annular groove, 20. 24, is a cam projection formed on the collar, 25. The projection, 24, forces the rocking arm and consequently the plunger in the direction indicated by arrow upon every revolution of the arbor, D², so that the lower portion of the lever is pressed in the direction indicated by arrow and withdraws the split 80 plunger from contact with the portions, y, y' , of the pivoted jaw immediately upon the button being completed. As soon as the jaws are again brought up into position opposite the plungers in the manner hereinbefore described the split plunger, 10, is again thrown against the portions, y, y' , so as to hold the blank securely in position during the period that the cutters are operating upon the blank. 85

In order to provide a means whereby the face of the button may be protected from being defaced after it has been finished and ejected through the hole, Y', I provide a shield, 26, made preferably of very thin metal which is secured on the ends of the pivot 90 arms, 27. 28, is an extension arm forming part of the pivoted arms, 27, and connected by the rod, 29, to the arm, 30, secured to the link, P. It will now be seen that upon the lower end of the lever being thrown back by 105 the cam and consequently the cutter withdrawn the shield, 26, will assume the position shown in the drawings before the cutter so that the button will be thrown against it and fall out without any danger of its coming in contact with the cutter. Normally the shield is held up from between the cutter, f, and the disk, S, but upon the face of every button being completed it will be thrown down into the position shown so that when 115 the cutter, g, is finishing the back it will force the button out so that it will strike the shield and fall down without it being defaced. 120

In order to provide a means whereby the disk may be prevented from vibrating in the slightest degree while the cutters are operating upon the blank between the jaws I provide a shoulder, 31, which is secured so that its end will rest against the opposite side of the disk to that on which the split plungers 125 are held against the adjustable jaws.

It will be understood from the description that each button is finished at the back and front practically simultaneously. It will also be understood that on account of the gradu- 130

ated longitudinal movement of the cutters, *f*, regulated by the cams, *K*, the face and back of each button will be perfectly finished.

It will also be understood that heretofore in machines in which the pressure has been maintained by a spring jaw alone it has been found that the blank has frequently been partially misplaced and as a consequence the blank spoiled but by my providing the supplemental split plungers, 10, operated as described I find in practice that I can maintain such a strong pressure upon the jaws that it is impossible for the blanks to get misplaced.

What I claim as my invention is—

1. In combination, the cutters, the disk carrying the movable clamping jaws, the means for rotating the disk step by step and the means for automatically opening the clamping jaws in succession as the disk rotates, said means being brought automatically into operative connection with the movable jaws by the rotation of the disk, substantially as described.

2. In combination, the cutters, the disk carrying the movable clamping jaws, the means for rotating the disk step by step, and the stationary cam arranged adjacent to the disk and in the path of a portion of each movable jaw to engage the same during part of the disk's revolution, the said movable jaws being carried from engagement with the stationary cam by the further revolution of the disk, substantially as described.

3. In combination, the cutters, the disk, the movable clamping jaws, the means for rotating the disk and the spring cam arranged adjacent to the disk to be brought automatically into operative connection with the movable jaws by the rotation of the disk to open them, said cam being adapted to be sprung aside for releasing said jaws while the disk is at rest, substantially as described.

4. In combination, the cutters, the rotary disk carrying a series of stationary open jaws, a series of movable jaws also carried by the disk and operating laterally thereof to and from the fixed jaws and the means for moving the disk, substantially as described.

5. In combination, the cutters, the means for holding the blank comprising two or more jaws arranged in pairs adapted to press on different parts of the blank, and the two plungers, one for each jaw with means for pressing said plungers independently substantially as described.

6. In combination, the cutters, the disk with means for operating the same the movable clamping jaws carried by the disk the plunger arranged adjacent to the disk at one of its stations and operating laterally thereof to press the jaws in succession as they are brought before it and the means for operating the plunger, substantially as described.

7. The combination with the disk provided with stationary open jaws and pivoted ad-

justable spring jaws and means whereby the jaws are opened and then closed during the period that the cutters are operating upon the preceding blank, of the cutters and cutter spindles deriving a longitudinal intermittent reciprocating movement through the levers operated from cams on one end of the main arbor which have worm gears at their other end driven from worms on the driving shaft as and for the purpose specified.

8. The combination with the disk provided with stationary jaws and pivoted adjustable spring jaws and plungers operating laterally of the disk to press the spring jaws, means for operating the disk step by step of the cutters and cutter spindles deriving a longitudinal intermittent reciprocating movement through the levers operated from cams on one end of the main arbor which have worm gears at their other end driven from worms on the driving shaft as and for the purpose specified.

9. The combination with the cutters, the disk provided with stationary open jaws and pivoted adjustable spring jaws and split plungers operated as described, of the projecting shoulder, 26, the end of which rests against the disk as and for the purpose specified.

10. The combination with the cutters, of the disk secured on the end of the spindle, *s*, and provided with stationary jaws and pivoted spring jaws which are adjustable as described, of the ratchet pinion and pawl which receive an intermittent motion from a cam on one of the main arbors so as to partially revolve the disk at each forward movement of the pawl as and for the purpose specified.

11. The combination with the disk provided with stationary jaws and adjustable spring jaws and the split plungers arranged to operate so as to hold the jaws stationary during the period that the cutters are operating upon the blank, of the spring stop arm the end of which is designed to fit into notches, *t*, in the disk as and for the purpose specified.

12. In a button turning machine the combination with the main shaft, *A*, provided with the worms, *B*, *B'*, of the arbors, *D*, *D'*, provided with the worm gears, *C*, *C'*, at one end meshing with the worms, and at the other end with the cams, *K*, *K'*, arranged to operate in connection with the levers, *H*, *H'*, and the cutter spindles, *F*, and, *G*, connected to the levers, *H*, *H'*, respectively deriving a longitudinal movement from the levers through their connection to the cams as and for the purpose specified.

13. In a button turning machine the combination with the main shaft, *A*, provided with the worms, *B*, *B'*, of the arbors, *D*, *D'*, provided with the worm gears, *C*, *C'*, at one end meshing with the worms, and at the other end with the cams, *K*, *K'*, arranged to operate in connection with the levers, *H*, *H'*, and the cutter spindles *F*, and, *G*, connected to the levers, *H*, *H'*, to be operated thereby and the

- pulleys, F', and, G', designed to rotate the cutters and cutter spindles F, and, G, respectively as and for the purpose specified.
14. The combination with the cutters, f, and, g, of the revolving disk, S, provided with open stationary jaws, Y, the pivoted adjustable jaws, y, y', the springs, z, designed to normally hold the jaws, y, y', against the stationary jaws Y, the pin, z', located behind the jaws, y, y', and extending through the disk, S, and the stationary cam designed to push the pin, z', inwardly as and for the purpose specified.
15. The combination with the cutters, f, and, g, of the revolving disk, S, provided with open stationary jaws, Y, the pivoted adjustable jaws, y, y', the springs, z, designed to normally hold the jaws, y, y', against the stationary jaws Y, the pin, z', located behind the jaws, y, y', and extending through the disk, S, and the stationary cam designed to co-act with the pin, z', and provided with a handle, Z', so as to release the pin z', as and for the purpose specified.
16. The combination with the cutters, f, and, g, the intermittently revolving disk, S, provided with open stationary jaws, Y, the pivoted adjustable jaws, y, y', the springs, z, designed to normally hold the jaws, y, y', against the stationary jaws, Y, of the split plunger, 10, comprised of the parts, 11, and, 12, the levers, 15, the upper ends of which fit into notches, 14, in the parts, 11, and, 12, and the spiral springs, 17, attached at one end to the lower ends of the levers, 15, and at the other end to a portion of the frame as and for the purpose specified.
17. The combination with the cutters, f, and, g, the intermittently revolving disk, S, provided with open stationary jaws, Y, the pivoted adjustable jaws, y, y', the springs, z, designed to normally hold the jaws, y, y', against the stationary jaws, Y, of the split plunger, 10, comprised of the parts, 11, and, 12, the levers, 15, the upper ends of which fit into notches, 14, in the parts, 11, and, 12, the spiral springs, 17, attached at one end to the lower ends of the levers, 15, and at the other end to a portion of the frame, the plunger, 18, connected at the top to the rocking arm, 21, on the arbor, D', and the cam projection, 24, on the arbor, D, designed to come in contact with the friction roller, 22, at the top of the arm, 21, as and for the purpose specified.
18. The combination with the cutters, f, and, g, of the disk, S, provided with the open jaws, Y, and, y, y', and secured on the end of the counter shaft, s, the ratchet pinion, s', secured on the opposite end of the counter shaft, s, and the pawl, s'', pivoted on the loose arm, T, and driven intermittently through the link, T', arm, U, on the one end of the spindle, u, and arm, U', at the other end provided with the pin, u', fitting into a cam groove, u'', made in the collar, V'', secured on the arbor, D, as and for the purpose specified.
19. The combination with the disk, S, driven as specified, and having notches, t, cut in its periphery, of the stop arm, V, secured on the one end of the rocking spindle, w, and having the spiral spring, W, located behind it as and for the purpose specified.
20. The combination with the disk, S, driven as specified and having notches, t, cut in its periphery, of the stop arm, V, secured at one end of the rocking spindle w, the arm, X, located at the other end of the rocking spindle w, and having a pin, x, which fits into the cam groove, x', formed in the collar, X', secured to the arbor, D, as and for the purpose specified.
21. The combination with the cutters, f, located on the inner end of the cutter spindle, F, and driven as specified, of the lever H, pivoted at the upper end of the standard, e, connected to the end of the cutter spindle, F, by the forked bracket, j, extending into the annular groove, f', and having at the top the curved arm, I, connected to the cross rod, J, by the spiral spring, i, and at the bottom, the cage, L, connected by the screw spindle, l, to the pivoted trunnion, M, in the lower end of the lever, H, the cage, L, being adjustably supported at its inner end and provided with the roller, 2, which is designed to co-act with the cam, K, on the arbor D, as and for the purpose specified.
22. The combination with the cutters and cutter spindles, f, and, F, and, g, and, G, of the levers, H, H', connected at the top by the arm, I, I', and spiral springs, i, i', to the cross rods, J, and at the bottom to the cages, L, L', by the screw spindles, l, l', and pivoted trunnions, M, M', the links, P, P', supporting the inner end of the cages, L, L', and the rollers, 2, and, 8, journaled at the inner end of the cages, L, L', of the cams, K, K', constructed as specified, and having the face rollers, k, k', and the cam arms, Q, Q', pivoted at r, r', and having the curved portions, R, R², and, R', and, R², R⁴, R⁵, arranged to co-act with the rollers, k, k', respectively as and for the purpose specified.
23. The levers, H, and, H', connected to the end of the cutter spindles, f, and, g, as specified, and pivoted at the top on the adjustable screw spindles, h', h, and at the bottom by the adjustable screw spindles, l, l', running through the trunnions, M, M', to the cages, L, L', provided with the rollers, 2, and, 8, designed to co-act with the cams, K, and, K', respectively as and for the purpose specified.
24. The combination with the lever, H, pivoted at the top of the standard, e, and connected to the end of the screw spindle, h, as specified, of the shield, 26, pivotally connected to the end of the arms, 27, which is pivoted on the rod, 28, having an arm 29 connected to the link, P, supporting the cage, L, which derives a forward and backward movement from the lever, H, as and for the purpose specified.
25. In combination, the clamps for holding the blank, the rotary reciprocating cutters

with connections for operating the same, the shield 26, the movable arm carrying said shield and movable laterally with relation to the cutters and the means for operating said arm to move the shield to and from position between the cutters, substantially as described.

26. In combination, the frame, the cutters, the rotary spindles carrying said cutters, the levers H; H' pivoted at their upper ends to

the frame and depending therefrom and the operating means for the levers connected with their lower ends, said levers having their intermediate portions connected with the rotary spindles, substantially as described.

DILMAN BRUBACHER SHANTZ.
